CLAIM

The ornamental design for a set of protection cushions with a handle, as shown and described.

DESCRIPTION

FIG. 1 is a top, front and left side axonometric view of a set of protection cushions with a handle, showing our new design;

FIG. 2 is a top, front, and right side axonometric view thereof;

FIG. 3 is a bottom, front, and left side axonometric view thereof;

FIG. 4 is a top, rear, and left side axonometric view thereof; FIG. 5 is a bottom, rear, and left side axonometric view thereof;

FIG. 6 is a bottom, rear, and right side axonometric view thereof;

FIG. 7 is a front view thereof;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The broken lines seen adjacent to the shaded surfaces and within those areas depict portions of the set of protection cushions with a handle that form no part of the claimed design. All other broken lines seen in the drawings depict unclaimed environmental subject matter only and form no part of the claim.
